Application June 13, 1945, Serial No. 599,287

7 Claims. (Cl. 177—380)

(Granted under the act of March 3, 1883, as
amended April 30, 1928; 370 O. G. 757)

1

This invention relates in general to a pulse transmission system and in particular to a means for producing a group of pulse signals wherein the number and the relative time occurrence of the pulse signals comprising the group are selectively determined.

In an application filed May 11, 1945, Serial No. 593,174, by E. H. Krause et al., a pulse transmission system is disclosed in which a group of pulse signals is transmitted over a given time interval. The number and the relative time occurrence of the pulses comprising the group are made controllable. In this system a time base made up of a number of successive unit time intervals is generated at the transmitter and comprises a time pattern from which the group to be transmitted is formed. In any given transmission a pulse signal is always transmitted coincident with the first unit time interval in the time base and at such other unit time intervals as may be desired. At the receiving system a second time-base generating device and a series of amplifying channels are provided and arranged so that each unit time interval generated by the time base device renders a different one of the amplifying channels operative. In operation the first pulse received from the transmitter starts the time base at the receiver then each pulse signal arriving after the first pulse signal is made to pass through a different amplifying channel according to its time relationship with respect to the first pulse in the group. In this manner any given pulse signal occupying a definite time position relative to the start of the interval of transmission can be made to pass through a particular amplifying channel and can therefore be used to perform a definite function at the receiving system.

It is an object of this invention to provide a means for producing a group of pulse signals wherein the number and relative time occurrence of the pulse signals are selectively determined.

It is another object of this invention to provide a means for alternately producing two distinct groups of pulse signals wherein the disposition of the pulse signals in each group is selectively determined.

Other objects and features of the present invention will become apparent upon a careful consideration of the following detailed description when taken together with the accompanying drawings.

Fig. 1 is a circuit diagram of one embodiment of the invention, and Figs. 2 and 3 show a series of wave forms illustrative of the operation of the circuit shown in Fig. 1.

2

According to the invention, a time base generator, which may comprise a delay line energized by a pulse generator or any other suitable arrangement as hereinafter described, is provided and arranged to cooperate with a series of pulse selector vacuum tubes. Associated with each of the tubes is a separate switching means which may be operated to effectively withdraw any one or number of tubes from the series. The vacuum tubes and the time base generator are so interconnected that when the latter is set into operation it functions to successively render conducting those tubes left in the series by the switching apparatus. Connected to the tubes in the series, but, not shown for purposes of simplification, is a pulse transmitter which is held under control of the pulse selector tubes and arranged to emit a pulse signal each time one of the tubes in the series becomes conducting.

With particular reference to Fig. 1 a detailed circuit diagram of the invention is shown. As indicated in the figure, the time base generator comprises a pulse generator 10, and a scale-of-five counter chain, including stages 11, 12, and 13. Tubes 14 through 18 represent the pulse selector tubes with which the time base generator is to operate, while tube 24 is representative of a coincidence tube which is connected in common to the pulse selector tubes by way of a biasing tube 23. Also, a pulse transmitter, not shown, is connected to the output terminal 55. As will hereinafter be described in detail, the pulse generator 10 may be a multivibrator or any other suitable pulse-generating device, such as that shown in the aforementioned patent application, which may be started and stopped either automatically or manually, such as by the off-on switch 71, for example. The primary function of this pulse generator is to provide a source for driving the counter chain, comprising stages 11, 12, and 13, through a complete cycle of operation and at the same time to provide transmitter keying pulses to the first control grid 35 of the coincidence tube 24. By interconnection of the control grid of each of the selector tubes 14 through 18 to predetermined points in the counter chain as hereinafter described in detail and in accordance with the principles taught in the patent application of E. H. Krause Serial No. 582,964, filed March 15, 1945, the counter circuit is made to successively render each of the selector tubes conducting, as far as their grids are concerned, during a cycle of operation. When any of the selector tubes conducts, a voltage drop appears 55 across their common plate load resistance 29.

The presence or absence of this voltage drop results respectively in either non-conduction or conduction of the biasing tube 23, which by way of its connection to the second control grid 34 of the coincidence tube 24, renders the latter either sensitive or insensitive, respectively, to positive voltage pulses applied to its first control grid 35 by the pulse generator 10. Any one of the selector tubes 14 through 18 can be prevented from going into conduction in response to the action of the counter chain by opening the cathode circuit of the respective selector tube. Therefore to selectively suppress or produce output pulses at the terminal 55 of the coincidence tube 24, a number of multi-position switches numbered 19 through 22 are inserted in the respective cathode circuits of the selector tubes 15 through 18. In the zero position of these switches the cathode circuit is complete to ground and the selector tube is capable of conduction in response to the action of the counter chain. In the No. 3 position of the switches the cathode circuit is open and the corresponding selector tube will be incapable of conduction regardless of its grid bias voltage as provided by the counter circuit. Consequently, during any given cycle of counter operation the appearance or absence of a transmitter keying signal at the output terminal 55 depends upon the setting of the cathode switches 19 through 22.

In the typical counter chain shown here all of the counter stages 11, 12, and 13 are similar in structure, also the grid biasing resistances and plate resistances employed at corresponding points in each half of each counter stage are of similar resistive value, resistances 43, 46 similar to 41, 45 and so on. Therefore for purposes of simplification, only the first counter stage 11 will be described in detail. In this stage the multi-grid tubes 11a and 11b represent the vacuum tube components of a conventional scale-of-two counter circuit. The first control grid 38 of tube 11a is connected through the shunt combination of resistance 43 and capacitance 44 to the plate of tube 11b and also, through the grid return resistance 46 to a source of C= potential. Likewise, the first control grid 39 of tube 11b is connected through the shunt combination of resistance 41 and capacitance 42 to the plate of tube 11a and also, through the grid return resistance 45 to a source of C= potential. The circuit is thus made regenerative and only one of the tubes will conduct at any instant. To change the conduction condition of either tube a negative signal is applied in parallel to the second control grids 36 and 37 of both tubes. As the conduction state of the circuit changes, the first control grid of the tube passing from conduction to nonconduction will vary from about zero potential to a negative potential determined by the voltage divider action from the positive potential at the plate of 11b to the negative supply potential across resistances 43, 46. The input to the counter circuit as obtained from the pulse generator 10 is applied in parallel to the control grids 36 and 37 through a coupling circuit comprising capacitance 60 and resistance 61. In one case this circuit may constitute a short time-constant compared to the time duration of the applied pulse and therefore function to produce an abrupt positive pulse in response to the positive-going edge of each of the applied pulses and an abrupt negative pulse in response to the negative-going edge of each of the applied pulses. The input to the second counter circuit 12 is taken from a tap on the plate load.

resistance of the second tube 11b in the first counter stage and is applied in parallel through a second short-time-constant circuit similar to capacitance 60 and resistance 61 to the second control grids of tubes 12a and 12b of the second counter stage 12. Finally, the input to the last counter stage 13 is taken from a tap on the plate load resistance of the second tube 12b in the second counter stage and applied in parallel through another short-time-constant circuit similar to capacitance 60 and resistance 61 to the second control grids of tubes 13a and 13b of the final counter stage 13. As hereinafter described, the quiescent or zero state for the counter chain exists when tubes 11a, 12a, and 13b are conducting and tubes 11b, 12b, and 13a are non-conducting. In tracing a complete cycle of counter operation, the first input pulse applied to counter stage 11 renders tubes 11b, 12b, and 13a conducting and tubes 11a, 12a, and 13b non-conducting. The second input pulse renders tubes 11a, 12b and 13a conducting. A third pulse from the pulse generator will render tubes 11b, 12a and 13a conducting. The fourth input pulse renders 11a, 12a and 13a conducting. The fifth negative input pulse would normally render tubes 11b, 12b and 13b conducting but due to a feedback pulse obtained from the plate of tube 13b and applied through capacitance 58 to the suppressor grids 59 and 63 of tubes 11b and 12b respectively, the tubes 11a, 12a and 13b will be conducting, and tubes 11b, 12b and 13a non-conducting. It will be noted that this state is identical to that which existed when the counter was in the zero or quiescent state. Thus the counter chain is of a scale-of-five variety.

In the selector circuit the control grid of each tube 14 through 18 is connected to a separate junction point 100, 200, 300, 400, and 500. Each of these junction points is in turn connected through three separate resistances to the first control grid of one of the tubes in each of the counter circuits 11, 12 and 13. This connection is typified at the first junction point 100 by resistances 47, 48 and 49. In this relation it should be noted that all the resistances at each junction point are equal in size and are current limiting in function. At the first junction point 100 current limiting resistance 47 is connected to the first control grid of tube 11a and resistance 48 to the first control grid of tube 12a and the third resistance 49 to the first control grid of tube 13b. As abovementioned, the first control grid of any tube in the counter circuit varies from zero potential to a potential determined by voltage division across resistances 43, 46 as that tube passes from conduction to non-conduction. Thus, when the counter is in the zero or quiescent state wherein the tubes 11a, 12a and 13b are conducting, the potential at the junction point 100 will be zero and the selector tube 14 will conduct since its cathode is returned directly to ground. If each of the resistance connections of the remaining junction points 200, 300, 400 and 500 are traced it will be found that in the zero state of the counter, a minimum of at least one resistance at each of the other junction points is returned to a grid in the counter circuit which is at a negative potential. The minimum negative voltage existing at any one of these junction points due to the voltage divider action of the current limiting resistances is therefore at least $\frac{1}{3}$ of the negative voltage existing at the junction of resistances 43, 46 when tube 11b is conducting. Thus, if the negative potential is made large relative to the cut-off bias for the selector tubes the grids

of the remaining tubes in the selector circuit will be biased below cut-off. Then as the counter circuit is driven into its No. 1 state where tubes 11b, 12b and 13a are conducting and tubes 11a, 12a and 13b are non-conducting, it will be observed that the voltage at the junction point 200 will now be at zero while the voltage existing at the other junction points 100, 300, 400 and 500 will be sufficiently negative to hold the other selector tubes below cutoff. Tube 15 will now be able to conduct as far as its grid is concerned. In the second state of the counter circuit tube 16 will be the only tube in the selector capable of conducting and so on down the circuit, each selector tube rendered capable of conducting in its proper order with each change in state of the counter circuit.

The coincidence tube 24 is preferably of the pentagrid type having two control grids 34 and 35. The first control grid 35 provides a means by which the pulse signals from the pulse generator 10 may be applied to it, while the second control grid 34 provides a means by which the coincidence tube may be blocked and unblocked, so as to speak, by the joint action of the counter circuit and the selector circuit to thereby controllably suppress or produce an output pulse at the terminal 55. The first control grid 35 is returned through resistance 62 to the juncture point of the cathode resistances 32 and 33. As a result of the voltage dividing action of these two resistances, and the cathode bias voltage 57, the coincidence tube is held unresponsive to negative signals applied to this grid. The second control grid 34 is directly connected to the plate of the biasing amplifier 23 which in turn is grid driven from the common plate load resistance 29 of the selector tubes. During the time when all of the selector tubes are non-conducting, the grid of tube 23 will rise above cathode potential until limiting by resistance 29 occurs. This results in heavy conduction by the biasing tube 23 producing a large voltage drop across its plate load resistance. The plate potential of tube 23 will then become only slightly higher than the positive cathode potential 56. This latter potential is made some suitable value less than the cathode potential 57 on the coincidence tube so that in this condition the bias on the second control grid 34 is such as to hold the coincidence tube blocked or non-conducting regardless of the signal applied to the first control grid 35. When, however, any one of the selector tubes becomes conducting, a voltage drop appears across their common plate load resistance 29. This drop is sufficient to bias tube 23 beyond cut-off potential. The plate voltage of this tube then rises to its plate supply voltage 64. This supply voltage is made equal to the cathode bias voltage 57 of the coincidence tube and the second control grid 34 of the latter is therefore possessed with zero bias and the coincidence tube is ready to respond to any positive signal applied to its first control grid 35.

For purposes of illustration assume that the cathode switches 20 and 21 in the selector tubes 15 and 17 are set in the zero position while switches 19 and 22 in the selector tubes 15 and 18 are set in the No. 3 position. With this assumption and the further assumption that the counter circuit is initially in its zero or quiescent state, the circuit will now be described with reference to the wave forms shown in Fig. 2. Waveform *a* is representative of the output signal from the pulse generator 10. This output wave is applied in parallel to the short time-constant circuit

comprising capacitance 60 and resistance 61 to the input of the counter circuit and also through the short time-constant circuit comprising capacitance 60 and resistance 62 to the first control grid 35 of the coincidence tube 24. Waveform *b* is the result of the action of the foregoing short time-constant circuits and is representative of the actual signal voltage applied to the input of the counter circuit and to the first control grid 35 of the coincidence tube 24. Since the counter circuit was initially assumed as being in the zero or quiescent state with the selector tube 14 conducting and therefore with the bias removed from the second control grid 34 of the coincidence tube 24 and since the first pulse in waveform *b* is positive and does not effect a change in the counter state, this pulse will appear at the output terminal 55 as a negative pulse such as that shown in waveform *c*. The next pulse in waveform *b* is negative and will therefore be blocked from the output terminal 55 of the coincidence tube 24 by the action of the cathode bias 57 but will, however, produce the number one state in the counter circuit wherein tubes 11b, 12b, and 13a are conducting and tubes 11a, 12a and 13b are non-conducting. This action will render the selector tube 15, as far as its control grid is concerned, conducting but since its cathode switch 19 was assumed adjusted to the No. 3 position its cathode circuit will not be complete and therefore the tube will not conduct. In this case, the second control grid 34 of the coincidence tube 24 will be biased negative and therefore the second positive pulse will not produce an output at the terminal 55. The second negative pulse operates to produce the second state in the counter circuit with tube 16 conducting as far as its grid is concerned and since this is one of the tubes whose cathode switch 20 was set in the zero position, the tube will conduct and the bias will be removed from the second control grid 34 of the coincidence tube with the result that the third positive pulse causes conduction by tube 24 producing, with negligible delay, a negative pulse at the output terminal 55. Thus the combined actions of the counter circuit and the selector circuit operate to produce at the output terminal 55 a pulse group formation such as that shown by waveform *c*. In this case the first, third and fourth pulses were produced at the output terminal 55 while the second and fifth were suppressed.

From the foregoing it was seen that whether or not a pulse appears at the output terminal 55 and is therefore transmitted depends upon the setting of the cathode switch arrangement in the selector circuit. In some instances it may be desired to transmit for a given interval of time one group of pulse signals and then to transmit for another interval of time a second group of pulse signals having a different formation. To accomplish the foregoing, a multivibrator comprising tubes 25 and 26 and a pair of diodes 27 and 28 are disposed within the cathode circuits of the selector tubes and are arranged so as to produce cathode switching in a predetermined manner. The multivibrator is preferably a symmetrical free-running type having a period much longer than the time required to make several successive transmissions during the conduction period by either of the tubes. When tube 25 is conducting, tube 26 will be non-conducting. During this time the voltage at the plate of tube 25 will be near that of its cathode which is biased negative as indicated at 70, while the plate of 75 the non-conducting tube will be substantially B+.

As arranged, the cathodes of the associated diodes 27 and 28 are connected through the respective current limiting resistances 30 and 31 to the plates of tubes 26 and 25. Thus when tube 26 is conducting its plate potential is nearly that of source 10 which is sufficiently negative to permit conduction by the associated diode 27. At the same instant tube 25 is non-conducting so that its plate potential will be at B+ with the result that the associated diode 28 is also held non-conducting. The diode that conducts appears essentially as a short circuit to ground while the non-conducting diode appears as an open circuit. Thus by connecting the cathode, for example, of diode 27 to all the Number 1 positions in parallel of the switches 19 through 22, and the cathode of diode 28 in parallel to all the No. 2 positions in the switches, the multivibrator action can make the No. 1 and 2 positions of the switches appear alternately as open and closed circuits respectively.

With reference to the waveforms shown in Fig. 3 the operation of the circuit including the action of the multivibrator and the associated diodes 27 and 28 will now be described. In Fig. 3, waveform *a* is representative of the alternating positive and negative voltage pulses obtained from the pulse generator 10 and applied in parallel to both the counter circuit and the coincidence tube 24. For purposes of illustration let it be assumed that the cathode switch 22 is set in the #2 position and the remaining cathode switches 19, 23 and 25 are set in the #1 position and that tube 25 in the multivibrator circuit is conducting. During this condition diode 28 appears as a short circuit and all the #2 positions in the switches 19 through 22 appear at ground while diode 27 and consequently all the Number 1 positions in the switch appear as an open circuit. In this case only the first pulse and the fifth pulse will be transmitted as represented by waveform *b*. Then, after a given number of such transmissions the multivibrator changes states wherein tube 26 is conducting and tube 25 is non-conducting. During this time diode 27 will conduct and the #1 terminals in the cathode switches will be substantially at ground potential while all the Number 2 positions appear as open circuits. The resulting transmission is that shown by waveform *c*. In this case the first, second, third and fourth pulses produce transmission, the fifth pulse is suppressed.

Although we have shown and described the use of a scale-of-five circuit as a time base generator it must be understood that if a counter circuit is to be used, one of a larger scale and a selector circuit having a correspondingly larger number of tubes may be employed without departing from the spirit of the invention. It is also to be understood that selection switches may be inserted in all of the selector tubes rather than all except the first tube as shown in the specific embodiment. Furthermore, it is not necessary to restrict the operation to a pulse generator providing alternate peaked positive and negative pulses to the counter circuit and the coincidence tube 24. For example, a series of pulses of negative polarity may be used to trip the counter circuit while an inverter tube can supply positive pulses to the second control grid 32 of the coincidence tube 24 or the negative pulses may be applied directly to the cathode of tube 24. Despite the fact that the counter pulses and the transmitter keying pulses occur simultaneously the system is still operative because a cer-

tain amount of time delay is inherent in the operation of the selector tubes. This delay is primarily due to the large resistances employed at 47, 48 and 49 and other similar positions which impose a finite time delay when charging or discharging the stray capacitances associated with these points. In addition this delay may be accentuated by actually inserting physical capacitances at these points. Therefore this invention is not to be limited to the embodiment shown except insofar as is necessitated by the spirit of the prior art and the scope of the appended claims.

The invention described herein may be manufactured and used by or for the Government of the United States of America for governmental purposes without the payment of any royalties thereon or therefor.

What is claimed is:

1. A means for producing a group of pulses wherein the number and relative time occurrence of the pulse signals in said group are selectively determined, comprising a means generating a time base which is comprised of a finite number of voltage pulses, each of which is predeterminedly spaced in time, a plurality of vacuum tubes, means associating each of said tubes with said first named means in such a manner as to be successively rendered conducting thereby, separate means associated with each of said tubes and arranged to render any one or number of said tubes unresponsive to the action of said first named means, a coincidence tube, means connecting the output from said first named means to said coincidence tube, and means connecting said coincidence tube in common with said plurality of tubes in such a manner that the pulse output from said first named means will appear at the output of said coincidence tube only during the time when one of said plurality of tubes is conducting.

2. A means for producing a group of pulses wherein the number and relative time occurrence of the pulse signals in said group are selectively determined, comprising a means generating a time base which is comprised of a finite number of voltage pulses each of which is predeterminedly spaced in time, a plurality of vacuum tubes, means associating each of said tubes with said first named means in such a manner as to be successively rendered conducting thereby, separate switching means associated with each of said tubes and arranged to render any one or number of said tubes unresponsive to the action of said first named means, a coincidence tube, means feeding the output from said first named means to said coincidence tube, and means connecting said coincidence tube in common with said plurality of tubes in such a manner that the pulse output from said first named means will appear at the output of said coincidence tube only during the time when one of said plurality of tubes is conducting.

3. A means for producing a group of pulses wherein the number and the relative time occurrence of the pulse signals in the group are selectively determined, comprising a plurality of the scale-of-two type of counter stages connected in cascade so as to form a scale-of-N counter circuit, a plurality of vacuum tubes each of which is connected to said counter circuit in such a manner as to be successively rendered conducting thereby as said counter circuit passes through a cycle of operation, separate switching means connected to each of said tubes for rendering any

one or number of said tubes unresponsive to the action of said counter circuit, a pulse generator arranged to produce a series of voltage pulses, means applying the output of said pulse generator to said counter circuit, a coincidence tube, means also applying the output from said pulse generator to said coincidence tube, and means connecting said coincidence tube in common with said plurality of tubes in such a manner that the pulse output from said pulse generator will appear at the output of said coincidence tube only during the time when one of said plurality of tubes is conducting.

4. A means for producing a group of pulses wherein the number and the relative time occurrence of the pulse signals in the group are selectively determined, comprising a plurality of the scale-of-two type of counter stages connected in cascade so as to form a scale-of-N counter circuit, a plurality of vacuum tubes each of which is connected to said counter circuit in such a manner as to be successively rendered conducting thereby as said counter circuit passes through a cycle of operation, separate switching means connected to each of said tubes for rendering any one or number of said tubes unresponsive to the action of said counter circuit, a pulse generator arranged to produce a series of voltage pulses, means applying the output of said pulse generator to one of said control electrodes in said coincidence tube, and means connecting the other control electrode of said coincidence tube in common to said plurality of tubes in such a manner that the pulse output from said pulse generator will appear at the out-put of said coincidence tube only during the time when one of said plurality of tubes is conducting.

5. A means for alternately producing two distinct groups of pulses wherein the number and the relative time occurrence of the pulse signals in each group are selectively determined, comprising a plurality of the scale-of-two type of counter stages connected in cascade so as to form a scale-of-N counter circuit, a plurality of vacuum tubes each of which is connected to said counter circuit in such a manner as to be successively rendered conducting thereby as said counter circuit passes through a cycle of operation, an electronic switching means, said switching means alternating back and forth between two electrical states, separate manual switching means connected to each of said tubes and to said electronic switching means, said manual switching means being arranged so that a first group of said tubes becomes unresponsive to the action of said counter circuit during one electrical state of said electronic switch and a second group of said tubes becomes unresponsive to the action of said counter circuit during the second electrical state of said electronic switch, a pulse generator arranged to produce a series of voltage pulses, means applying the output from said pulse generator to said counter circuit, a coincidence tube, means also applying the output from said pulse

generator to said coincidence tube, and means connecting said coincidence tube in common with said plurality of tubes in such a manner that the pulse output from said pulse generator will appear at the output of said coincidence tube only during the time when one of said plurality of tubes is conducting.

6. A means for alternately producing two distinct groups of pulses wherein the number and the relative time occurrence of the pulse signals in each group are selectively determined, comprising a plurality of the scale-of-two type of counter stages connected in cascade so as to form a scale-of-N counter circuit, a plurality of vacuum tubes each of which is connected to said counter circuit in such a manner as to be successively rendered conducting thereby as said counter circuit passes through a cycle of operation, an electronic switching means, said switching means alternating back and forth between two electrical states, separate manual switching means connected to each of said selector tubes and to said electronic switching means, said manual switching means being arranged so that a first group of said tubes becomes unresponsive to the action of said counter circuit during one electrical state of said electronic switch and a second group of said tubes becomes unresponsive to said counter circuit during the second electrical state of said electronic switch, a pulse generator arranged to produce a series of voltage pulses, means applying the output of said pulse generator to said counter circuit, a coincidence tube having at least two control electrodes, means applying the output from said pulse generator to one of said control electrodes in said coincidence tube, and means connecting the other control electrode in common to said plurality of tubes in such a manner that the pulse output from said pulse generator will only appear at the output of said coincidence tube during the time when one of said plurality of tubes is conducting.

7. A means for producing a group of pulses wherein the number and relative time occurrence of the pulse signals in said group are selectively determined, comprising a means generating a time base which is comprised of a finite number of voltage pulses each of which is predeterminedly spaced in time, a plurality of vacuum tubes, counter means interconnecting each of said tubes to said first named means whereby each of said tubes is caused to be successively rendered conducting as said counter means is driven through a cycle of operation, separate switching means associated with each of said tubes and arranged to render any one or number of said tubes unresponsive to the action of said first named means, a coincidence tube, means feeding the output from said first named means to said coincidence tube, and means connecting said coincidence tube in common with said plurality of tubes in such a manner that the pulse output from said first named means will appear at the output of said coincidence tube only during the time when one of said plurality of tubes is conducting.
